UNITED STATES PATENT OFFICE.

JOHNSTON ROBERTSON ALEXANDER, OF BIRKENHEAD, ENGLAND, ASSIGNOR TO JOHN GEORGE AULSEBROOK KITCHEN, OF LANCASTER, ENGLAND; GORDON HENRY FRASER, OF LIVERPOOL, ENGLAND, AND JAMES RYDER O'HANLON, OF WESTWOLD, LIVERPOOL, ENGLAND.

OUTBOARD-MOTOR DRIVING, STEERING, AND REVERSING MECHANISM.

Application filed May 4, 1923. Serial No. 636,711.

To all whom it may concern:

Be it known that I, JOHNSTON ROBERTSON ALEXANDER, a subject of the King of Great Britain and Ireland, and resident of 12 5 Cearns Road, Birkenhead, in the county of Chester, England, have invented certain new and useful Improvements Relating to Outboard-Motor Driving, Steering, and Reversing Mechanisms, of which the following is 10 a specification.

This invention relates to outboard motors for propelling vessels and has for its object to provide an improved combination and arrangement of parts whereby the outboard motor and the propeller driven thereby can be rotated in a constant direction and at constant speed and the steering, reversing and speed variation be effected independently thereof and without swivelling 15 the propeller.

My invention comprises the improved combinations and arrangements of parts hereinafter described and claimed.

Referring to the accompanying sheets of 25 explanatory drawings:—

Figure 1 is an elevation of the stern of a boat with an outboard motor equipment constructed and arranged in accordance with 30 my invention, the engine being omitted for simplicity in the illustration.

Figure 2 is a plan view of the rudder operating gear.

The same reference letters in the two 35 views indicate the same parts.

The outboard motor equipment is adapted to be secured to the stern of the boat by the frame *a* and clamp *b*. The frame *a* has two similar brackets *c* thereon (one only being shown in Figure 1) each with a slot *d* therein to which the hollow column *e* is 40 adjustably secured. The said frame also carries the pivot pin *f* of the member *g* which receives the upper end of the column *e* and also forms at its upper end the support 45 for the engine which is not shown in detail but is indicated by the broken off part *h*. When the connection of the column *e* to the brackets *c* is adjusted, the member *g* turns 50 about the pivot *f*.

Through the column *e* passes the driving shaft *i* by which the propeller *j* is rotated by suitable gearing. The propeller shaft 55 journal and thrust bearings are carried in

the casing *k* secured upon the lower end of the column *e*. Such casing also carries a 55 projecting arm *m* in which is secured the pivot pin *n* for the lower end of the duplex rudder plates *o*, *p*. The upper ends of the latter are secured to two concentric rudder stocks *q*, *r*, the outer one (*q*) of which is 60 carried in brackets *s*, *t* attached to the column *e* and to the member *g* respectively. The upper ends of the stocks *q*, *r* carry arms 65 *u*, *v* which are connected by links *w*, *x* both to arms *y*, *z* pivoted about a dummy rudder stock *3* carried by the member *g* and to links 70 *4*, *5* pivotally attached to a nut *6* on a screw *7* which is rotatable by a hand wheel *8*. The arms *y*, *z* are similar and parallel to the arms *v*, *u*. The tiller through which the 75 screwed spindle *7* passes is made in two parts *9*, *10*, the part *9* screwing into *10* and the latter having slots at its opposite sides for the lugs on the nut *6* to which links *4* and *5* are attached. The part *10* is pivoted about 80 the dummy stock *3*.

With the arrangement hereinbefore described, the outboard equipment is a self-contained unit of which the engine and propeller are adapted to be directly coupled for 85 continuous operation at normal maximum speed, the propeller axis being fixed. For steering purposes the tiller *9*, *10* is turned about its pivot which is the dummy stock *3* and such turning movement is transmitted 90 by the links *4*, *5* and the parallel linkage system *y*, *w*, *v* and *z*, *x*, *w* to the concentric rudder stocks *r*, *q* and so to the rudder blades *p*, *o* which deflect the propeller stream and so by their reaction effect the desired 95 steering operation. For speed variation and boat reversing purposes, the hand wheel *8* is rotated. This by means of the nut *6* on the screw *7*, and the linkage system before referred to causes the rudder blades to be turned through equal angles in opposite directions whereby the rudder blades are brought close together behind the propeller to retard or when forming a closed pocket 100 behind the propeller, to reverse the propeller stream. If the tiller be turned about the dummy stock *3* at the same time that the hand wheel *8* is rotated combined speed variation and steering control is effected.

My improved arrangement is compact 105 and efficient and simplifies the control of a

boat fitted with outboard motor equipment.

I claim:—

1. Outboard motor equipment for vessels comprising, in combination, a frame with 5 clamping means thereon, a member pivotally attached to said frame, a column carried by said member and adjustably secured to said frame, an engine upon said member, a casing attached to said column carrying the 10 propeller and propeller shaft, an engine driven shaft through said column rotating said propeller, duplex rudder plates pivotally carried at their lower ends by a bracket from the propeller casing, concentric rudder 15 stocks astern of and supported from said column and secured to the upper ends of said rudder plates, a dummy rudder stock forward of said column and carried by the aforesaid member, a parallel linkage system 20 between said concentric rudder stocks and dummy rudder stock, a tiller fulcrumed
- about said dummy rudder stock, means longitudinally movable upon said tiller, and links connecting said longitudinally movable means to said parallel linkage system, 25 as set forth.
2. In an outboard motor equipment as claimed in claim 1, a screw rotatable within the tiller, a hand wheel upon the end of the tiller to rotate the said screw, a nut 30 upon said screw connected to the parallel linkage system, and means preventing the nut's rotation, as set forth.
3. In an outboard motor equipment as claimed in claim 1, a parallel linkage system 35 consisting of similar and parallel arms upon the concentric rudder stocks and dummy stock and links connecting said parallel arms, as set forth.

In testimony whereof I have signed my 40 name to this specification.

JOHNSTON ROBERTSON ALEXANDER.
